UNITED STATES PATENT OFFICE.

ROBERT McLAREN, OF BLACKFORD, SCOTLAND, ASSIGNOR TO GLENEAGLES SHOE COMPANY LIMITED, OF BLACKFORD, SCOTLAND.

SHOE FOR PERSONAL WEAR.

Application filed October 17, 1927, Serial No. 226,642, and in Great Britain October 8, 1928.

This invention relates to shoes for personal wear and has for its general object to improve the fit of the top of a shoe and to prevent the shoe from slipping at the heel.

5 A more specific object of the invention is to provide a shoe with improved means of the kind comprising a strap or the equivalent applied at or near the top of a shoe, more or less surrounding the opening, and formed or

10 provided with one or more eyelets or the equivalent through which the ordinary shoe lace can be threaded in such a manner as to tighten the upper about the ankle of the wearer when the lace is tied.

15 Although a construction of this kind is preferred the invention is not restricted thereto since a buckle or the equivalent means for securing and drawing up the ends of the strap or the equivalent may be utilized 20 as hereinafter mentioned instead of the shoe lace.

The present invention provides a shoe in which the strap or the equivalent is so applied at or near the top of the shoe that it 25 extends for the most part between the shoe lining and quarter, being thus hidden from view and protected, whilst being adapted to keep the top of the shoe a snug fit on the foot of the wearer.

30 The strap or the equivalent may be in one or more portions and although the invention contemplates the use of a strap or strip of substantially inextensible material on one side only of the shoe, it is preferred to uti-

35 lize two such straps one on each side, each of which is secured at the back of the shoe whilst the respective free ends by which they are drawn taut are passed through slits, either in the lining to the interior of the shoe

40 to be secured above the tongue, or in the quarter to the outside of the shoe. Preferably in either case the ends are drawn taut by threading the ordinary shoe lace through eyelets in said ends prior to tying it. Obvi-

45 ously a single strap passing right round the heel and secured at the back of the shoe may be utilized instead of the two straps one on each side.

In some instances it has been found desirable 50 to insert in the shoe what may be termed "filling" means to avoid any ridge or "lumpiness" due to the ankle strap, and suitable means of this nature form a further feature of the present invention.

55 In order that the invention may be fully

understood and readily carried into effect the same will now be described with reference to the accompanying drawings, illustrating two preferred embodiments.

In the accompanying drawings:

60 Fig. 1 is a perspective view of a shoe having means according to the invention applied thereto, and illustrating the neat appearance of such a shoe;

Fig. 2 is an elevational view of one side of 65 the lining of such a shoe prior to fitting and regarded from the interior;

Fig. 3 is a plan view illustrating diagrammatically one manner of applying the invention to a shoe, and also the way in which the 70 shoe lace may be threaded to secure the desired effect;

Fig. 4 is a similar view to Fig. 1 of a shoe having the invention applied thereto in a slightly modified manner and also illustrating 75 in dotted lines preferred filling means;

Fig. 5 is an elevational view of one side of the quarter of the shoe illustrated in Fig. 4 regarded from the interior before the lining is applied thereto; and

80 Fig. 6 is a view similar to Fig. 3 but shewing a single strap the ends of which pass through slits in the quarter to the outside of the shoe.

85 Referring more particularly to Figs. 1 to 3 of the accompanying drawings in all of which the same reference characters indicate similar parts in the various figures, the shoe 1 has the shoe quarter 2 and the lining 3. The strap or the equivalent illustrated consists of a strip 4 of substantially inextensible material on each side of the shoe quarter 2 affixed to the lining 3 at the back of the shoe at 4^a (by stitches for example) and passing between the outside quarter 2 and lining 3 to a point below the top eyelet 7 of the shoe 1, where the end 5 is brought through a slit to the inside of the shoe (see Fig. 2). The end 5 of each such strip may be provided with an eyelet 6.

90 95 100 105 110 These strips may be drawn taut by the ordinary shoe lacing 8, 9, which may be utilised in conjunction with said strips 4 for the purpose hereinbefore specified. In this case each end 8 and 9 of the lace from an eyelet 7 on one side of the shoe may be passed through the eyelet 6 in the strip 4 on the opposite side of the shoe before being passed through the top eyelet 7 on the first mentioned side, the lace being thus crossed. Fig.

3 illustrates this diagrammatically, the end 9 of the lace being shewn by a chain line.

It will be evident that if it be found that only one side of the shoe opening tends to sag 5 or gape away from the foot a single strip 4 on that side may be employed, or that a single strip 4 passing right round the back of the shoe between the lining 3 and quarter 2 may be utilized as illustrated in Fig. 6, either 10 arrangement obviously falling within the scope of the invention.

Referring now more particularly to Figs. 4, 5 and 6 it will be noted that the free ends 15 of the strip or strap 4, that may be in one or two portions secured at the back of the shoe at 4^a, pass through slits in the quarter 2 to the outside of the shoe where they may be drawn taut by threading the ends of the shoe lace through their eyelets as illustrated 20 prior to tying it, or if desired by a buckle or the equivalent.

It will be noted from Fig. 5 and the brief description thereof that the strap or strip 4 is in this instance mounted on the quarter, 25 being secured thereto at 4^a and passing through slits in the quarter adjacent the top eyelets of the shoe. It is also preferred to provide guide bands 10 secured to the quarter and to pass the strap 4 therethrough 30 so that when it is tightened the quarter cannot belly out away from the lining. Such guide bands 10 are preferably made of thin fabric.

These modifications are more or less obvious 35 developments to those versed in the art but the chief distinguishing feature of this embodiment illustrated most clearly in Fig. 5 is the provision below the strap or the equivalent of "filling" means.

As illustrated these means take the form 40 of a strip 11 of leather or other suitable material of appropriate thickness applied to the inside of the shoe quarter 2 below the strap 4 above mentioned. Such a filling strip 45 11 preferably extends from the heel to a point slightly beyond the slit 4^b in the quarter 2 and if of leather is preferably skived off towards the ends 12 and 13 and towards the bottom 14 so as to provide 50 a gradual decrease of thickness so that the filling strip merges practically imperceptibly into the quarter without leaving any definite ridge or lumpiness. The filling strip also stiffens the quarter to some 55 extent. It will be understood from the above that it is assumed that the shoe shewn in Figs. 4 and 5 will be constructed with a separate quarter on each side each of which should be provided with a filling strip as 60 well as with a strap or equivalent, though a continuous filling strip and a continuous strap may be employed if desired passing right round the heel between the quarter and lining as shewn in Fig. 6. The filling strip

may be secured in any convenient manner 65 and in effect a guide is formed for the strap between its upper edge and the top edge of the shoe to which the lining would usually be stitched. The filling strip or strips may for example be secured by adhesive or 70 stitches, or both.

In Figs. 4 and 5 a line of stitches 15 is shewn at the top of the shoe and these 75 stitches may conveniently secure the lining to the quarter and the top ends of the guide bands 10, while the double row of stitches 16 may be utilized to secure the bottom ends of the guide bands and the top edge of the filling strip 11.

The usual lining is fitted inside the shoe, 80 while it will be found that the usual heel stiffening piece which is inserted between the quarter and the lining ensures a smooth and comfortable surface for the lining at the heel.

It will be understood that although it is preferred for the sake of neatness and convenience to provide the ends of the straps with eyelets and to utilize the ordinary shoe lace for tightening them any obvious equivalent such as a buckle could be employed for that purpose.

Various other modifications may obviously be made as desired while bearing in mind that in accordance with the characteristic 95 feature of the invention the strap or the equivalent is concealed from view between the shoe quarter and lining except for the ends by which it is drawn taut.

It will now be understood that the invention 100 provides means for preventing stones, sand or other matter from working into shoes in wear owing to the snug fit attainable, without affecting their neat appearance or the ease with which they can be 105 cleaned.

Furthermore the cost of production of 110 shoes is not increased substantially by applying the invention thereto.

It will be understood that the terms in the 115 appended claim are employed by way of illustration and not of limitation for example the term "strap" should be read broadly to cover any obvious equivalent.

I claim:—

In a shoe, a substantially in-extensible strap secured to the inner upper margin of the quarter and adapted to be tightened by the shoe lace, and a filling strip of substantially the same thickness as said strap secured to the quarter beneath said strap and abutting the lower edge thereof, the filling strip being skived off towards its ends and its lower edge substantially as and for the purpose described.

In testimony whereof, I have signed this specification.

ROBERT McLAREN.
